UNITED STATES PATENT OFFICE.

AUSTIN S. GOODMAN, OF OKLAHOMA, OKLAHOMA.

GRAIN-SEPARATOR.

1,243,284.

Specification of Letters Patent. Patented Oct. 16, 1917.

Application filed January 29, 1916, Serial No. 75,015. Renewed August 6, 1917. Serial No. 184,788.

To all whom it may concern:

Be it known that I, AUSTIN S. GOODMAN, a citizen of the United States, residing at Oklahoma, in the county of Oklahoma and State of Oklahoma, have invented certain new and useful Improvements in Grain-Separators; and I do hereby declare the following to be a full, clear, and exact description of the invention, such as will enable others skilled in the art to which it appertains to make and use the same.

This invention relates to grain separators provided with shaking sieves; and it consists in the novel construction and combination of the parts hereinafter fully described and claimed whereby the position of the sieve may be regulated without stopping the machine.

In the drawings, Figure 1 is a longitudinal section through a portion of a grain separator constructed according to this invention. Fig. 2 is a cross-section through the machine, taken on the line $x-x$ in Fig. 1.

The separator is provided with a casing 2, and has threshing mechanism and straw-racks of any approved construction. A shoe 3 is arranged in the rear part of the casing, and a chaffer screen 4 of any approved construction is secured in the shoe 3. This shoe is supported and reciprocated longitudinally in any approved way, and in the form of the device shown the shoe is provided with a cross-shaft 5 which slides and revolves in slots 6 or other suitable openings 85 in the sides of the casing 2. The cross-shaft 5 is journaled in the sides of the shoe and it reciprocates with the shoe. The cross-shaft also supports the shoe and the chaffer screen pivotally, and permits a tossing motion to be given to all the separating devices carried by the shoe. A portion of a rod 7 is shown as a means for reciprocating or shaking the shoe, but the shoe may be worked by any approved means.

A blast of air is driven through the chaffer screen in the direction of the arrows by any approved blower or fan.

A sieve 8 is supported in the shoe under the chaffer screen, and the rear end portion of this sieve is pivoted to the shoe by pins 9. The front end portion of the sieve is supported from the cross-shaft 5 by flexible connections 10. These connections may be cords, chains, or any similar devices, and their upper ends are wound upon the cross-shaft 5.

The cross-shaft 5 has a handle 12 arranged outside the casing for revolving it by hand, and a toothed wheel 14 is secured on the cross-shaft. A pawl 15 is pivoted to one side of the shoe, and engages with the teeth of the wheel 14, so that the cross-shaft is held from revolving, and the front end of the sieve is supported at a pre-arranged distance from the underside of the chaffer screen.

The pawl is operated by hand, and the position of the sieve is adjusted, without stopping the machine, by turning the cross-shaft by means of its handle.

The lower ends of the flexible connections 10 are connected to the sieve 8 by means of brackets 16 provided with notches 17. If desired, a second sieve 18 can be slipped into engagement with the notches 17, and its rear end can be hooked onto pins 20 which project from the shoe 3. This sieve is removable and can be slipped in and out of place as often as necessary.

In the preferred form of the device, as shown, the shoe 3 is supported pivotally upon the cross-shaft 5, the said shaft being arranged at about the middle of the shoe so that its end portions balance each other.

What I claim is:

1. The combination, with a casing, of a shaking shoe supported in the casing, a sieve having its rear end portion pivoted to the shoe, a cross-shaft extending through the casing and journaled in and reciprocating with the shoe, flexible connections wound on the cross-shaft and attached to the front end portions of the said sieve, and means for actuating the cross-shaft to vary the position of the sieve without stopping the machine.

2. The combination, with a casing provided with slots in its sides, of a shaking shoe arranged in the casing, a cross-shaft pivotally supporting the said shoe, said cross-shaft being journaled in and reciprocating with the said shoe and sliding in the slots of the casing, a chaffer screen arranged above the said cross-shaft and in the said shoe, a sieve having its rear end portion pivoted to the shoe, flexible connections wound on the cross-shaft and attached to the front end portions of the said sieve, and means for actuating the cross-shaft to vary the position of the sieve without stopping the machine.

3. The combination, with a casing, of a

shaking shoe supported in the casing, a sieve having its rear end portion pivoted to the shoe, brackets secured to the front end portion of the sieve, a removable sieve having 5 its rear end portion pivoted to the said shoe with its front end portion engaging slidably with the said brackets, a cross-shaft extending through the casing and journaled in and reciprocating with the

shoe, flexible connections wound on the 10 cross-shaft and attached to the said brackets, and means for actuating the cross-shaft to vary the position of the two sieves without stopping the machine.

In testimony whereof I have affixed my 15 signature.

AUSTIN S. GOODMAN.
